SEWING MACHINE MECHANISM

John F. Hand, Philadelphia, Pa., assignor to The
De Long Hook and Eye Company, a corporation
of Pennsylvania

Application April 1, 1936, Serial No. 72,036

5 Claims. (Cl. 112—2)

The invention relates to sewing machine mechanism and involves various improvements for automatically adjusting the work feeding device in order to adapt such mechanism for making 5 stitches of variable length at predetermined intervals in the stitching operation.

The invention has for one of its principal objects the provision of an elongated stitch at regular intervals in a line of stitches otherwise of 10 uniform length. One of the intended purposes of such elongated stitches is the provision of gaps in a line of stitching used for securing two pieces of fabric together, so that these gaps may be utilized to receive the hooked ends of hook 15 fastener devices when fastener tape with such fastener devices thereon is secured to the edge of the stitched material. This object of the invention is accomplished by the provision of mechanism for periodically increasing the extent 20 of feed of the work as predetermined stitches are formed.

The invention has for a further object the provision of improved mechanism for periodically varying the extent of movement of the intermittent feeding means of a sewing machine. As disclosed herein, the improvements are incorporated in a sewing machine of the type in which a link-bar is utilized for providing intermittent feeding movement of the feeding device. A particular object of the invention, therefore, is the provision of improved mechanism for periodically adjusting the fulcrum of this link-bar to thereby vary the extent of movement of the feeding device at each intermittent operation 35 thereof.

A further object of the invention is the provision of means for effecting manual adjustment of the elongated stitches with respect to the stitches of normal length in the line of stitching.

40 A still further object of the invention is the provision of novel means for effecting manual adjustment of the extent of movement of the work feeding device to thereby vary the length of all the stitches in the line of stitching.

45 Still further objects and advantages of the various features of the invention will be apparent from the following description, taken with the accompanying drawings wherein:

Fig. 1 is a front elevational view of a sewing 50 machine with the improvements incorporated therein, parts of the machine being broken away for clarity;

Fig. 2 is a plan view of the machine shown in Fig. 1, with the overhanging bracket arm broken 55 away;

Fig. 3 is a horizontal sectional view of the machine shown in Fig. 1, taken just below the base plate, and showing the work feed device in plan view;

Fig. 4 is a vertical sectional view of the machine taken on the line 4—4 of Fig. 1;

Fig. 5 is a vertical sectional view of the machine taken on the line 5—5 of Fig. 1;

Fig. 6 is a vertical sectional view of the machine taken on the line 6—6 of Fig. 1;

Fig. 7 is an end elevational view of the brake mechanism for the cam shaft of the improved mechanism, the cam shaft being shown in cross-section;

Fig. 8 is a plan view showing a section of two 15 pieces of material stitched together with the improved feed mechanism; and

Fig. 9 is a perspective view illustrating the manner in which the operative portions of hook fastener elements may be inserted through the 20 gaps in a line of stitching made with the improved mechanism.

As illustrated in the drawings, the present improvements are incorporated in a sewing machine having the usual bed plate 10 upon one end 25 of which is mounted the hollow standard 11 carrying the overhanging bracket arm 12 upon the outer end of which the head 13 is supported. A needle bar 14 is mounted for reciprocating movement in the head 13, and a presser foot bar 30 15 carrying a presser foot 16 is supported in the head in a manner permitting it to be raised and lowered by means of the presser foot lever 17.

Any well-known means may be employed for reciprocating the needle bar 14 from the main 35 drive shaft 18 supported in suitable bearings in the standard 11 and the bracket arm 12. Continuous rotary movement of the drive shaft 18 is provided by means of a pulley 19 secured on the outer end thereof and to which power may be 40 transmitted by a belt from any suitable source.

As disclosed herein, the improvements are utilized with an intermittently actuated feeding device comprising a feed dog 20 secured upon a feed bar 21. The teeth of the feed dog 20 project upwardly through suitable slots in a feed plate 22 during the operation of advancing the work *w* to the stitch forming mechanism comprising the needle 23 and the loop forming device 24.

Horizontal reciprocating movements of the feed bar 21 are provided by means of a rock shaft 25 supported at its opposite ends upon bearing screws 26 adjustably threaded in bearing members 27 projecting downwardly from the base 50 55

plate 10. The rear end of the feed bar 21 is pivotally connected to spaced rocker arms 28 on the rock shaft 25 by means of a pair of bearing screws 28 threaded in the arms 28.

5 The vertical movements of the feed bar 21 are provided by means of a rock shaft 30 beneath the front edge of the base plate 10 and having its opposite ends supported upon bearing screws 31 adjustably threaded in bearing members 32

10 projecting downwardly from the base plate 10. The end of the rock shaft 30 adjacent the feed bar 21 is provided with a rocker arm 33 having an anti-friction roller 34 mounted on the outer end thereof for cooperation with a slot 35 in the forward end of the feed bar so that rocking movements of the rock shaft 30 operate to raise and lower the forward end of the feed bar and thereby bring the feed dog 20 into and out of work feeding position in a manner well understood in

15 the art.

Rocking movement of the rock shaft 30 is produced by means of an eccentric rod 36 having its lower end pivoted to the free end of an arm 37 on the rock shaft 30 and its upper end connected 25 to an eccentric strap 38 which encircles an eccentric 39 on the drive shaft 18. Rocking movement is given to the rock shaft 25 by a link-bar 40 the lower end of which is pivoted to the free end of a rocker arm 41 on the rock shaft 25 and the upper 30 end of which is in the form of a yoke 42 forming a guideway for a cross-head 43 actuated by an eccentric 44 on the drive shaft 18.

The link-bar 40 is fulcrumed on the upper end of a link 45 the lower end of which is pivotally secured to the outer end of one arm 46 of a bell-crank adjusting lever 47. The lever 47 is pivotally supported on the standard 11 by means of a screw 48, as shown in Figs. 1 and 2 of the drawings. In machines of this general character the bell-crank lever 47 is commonly adjusted into 40 different positions by means of a set screw extending outwardly from the lever arm 49 through a slot 50 in the standard 11, the lever 47 being retained in any desired position by engagement 45 of the head of the adjusting screw with the edges of the slot 50. As is well understood, adjustment of lever 47 operates, through the link 45, to move the fulcrum of link-bar 40 nearer to or further from the axis of the shaft 18, and thereby decrease or increase the extent of feeding movement of the feed dog 20.

In accordance with the present improvements, the usual manual adjusting screw for lever 47 is replaced by a short rod 51 having its inner end threaded in the arm 49 of the adjusting lever. The outer end of rod 51 is provided with a head 52 pivotally connected to the upper end of a turn-buckle structure 53 forming a part of a cam rod by means of which motion is transmitted 60 periodically to the lever 47 for the purpose of effecting adjustment of the fulcrum of the link-bar 40. The lower end of the turn-buckle structure 53 is pivotally connected to the upper end of a slide bar 54 operating in a guide member 55 the lower end of which is secured to the base plate 10.

A cam roller 56 is mounted on the outer end of a pin 57 secured on the slide bar 54 and cooperates with the cam surface of a plate cam 58 secured on one end of a cam shaft 59 extending 70 parallel with the drive shaft 18. The cam shaft 59 is suitably supported in the upper end of bearing brackets 60 secured to the base plate 10 and extending upwardly therefrom.

The cam shaft 59 is intermittently rotated by 75 means of a ratchet wheel 61 secured thereon for

cooperation with an actuating pawl 62 pivoted on the outer end of one arm 63 of a bell-crank lever 64 freely movable on the cam shaft 59. The free end of the pawl 62 is maintained in engagement with the ratchet wheel 61 by a split leaf spring 65 having one end portion secured to the arm 63 and the other end portion in engagement with the pawl 62.

The arm 66 of the bell-crank lever 64 is provided with a pin 67 to which one end of a pitman 10 68 is connected. The opposite end of the pitman 68 is connected to a disc 69 on one end of a stub shaft 70 by means of a crank pin 71. The stub shaft 70 is suitably supported in a bearing block 72 secured on the upper side of the base plate 10. 15

The stub shaft 70 is rotated by means of a set of worm gears 73, 74, the former being secured on the stub shaft and the latter being secured to a vertical shaft 75. The lower end of vertical shaft 75 has a bearing support in the bearing block 72 and the shaft is supported near its upper end in a bearing bracket 76 secured to the under side of the bracket arm 12. The upper end of shaft 75 extends into the bracket arm 12 through an opening 77 and has fixed thereon a bevel gear 78 which meshes with a corresponding bevel gear 79 on the drive shaft 18.

As will be apparent from the structure heretofore described, the continuous rotary motion of the drive shaft 18 is transmitted directly to the vertical shaft 75, thence to the horizontal stub shaft 70, and intermittent rotary motion is thereupon imparted to the cam shaft 59 through the pitman 68, the bell-crank lever 64, the pawl 62 and the ratchet wheel 61. Preferably the number of teeth upon the ratchet wheel 61 corresponds to the number of stitches made by the stitch forming mechanism during each complete rotation of cam shaft 59. As illustrated in the drawings, the mechanism has been designed for a cycle of eight stitches, seven being of normal length as shown by *a* in Fig. 8, and the eighth stitch being elongated, as shown by *b*, for the purpose of forming a hook receiving gap.

The manner in which the elongated stitch *b* is formed will be clear, to those skilled in the art, from the operation of the structure heretofore described. It will be noted, however, that the projection on the cam 58 is so designed as to pass by the cam roller 56 during a single actuation of the pawl 62. During this interval, that is, in the interval during which the cam roller 56 is passing over the projection on the cam 58, the adjusting lever 47 is so actuated as to move the fulcrum of the link-bar 40 away from the axis 55 of the shaft 18 to thereby increase the throw of the lower end of the link-bar 40 and consequently increase the extent of movement of the feed dog 20 between two consecutive reciprocations of the slide bar 54. As a result, the particular stitch 60 then being made will be elongated to an extent determined by the design of the cam 58 and the adjusting lever 47.

The illustrated mechanism therefore provides a simple automatic means which is positively actuated by a moving part of the machine for periodically adjusting the fulcrum of the link-bar and thereby varying the extent of movement of the feed dog at predetermined intervals without disrupting the operation of the machine in the 70 formation of intervening normal stitches. It will also be apparent to those skilled in the art that manual rotation of the nut of the turn-buckle structure 53 provides a simple means for manually adjusting the length of all the stitches in 75

the line of stitching. Inasmuch as rotation of the turn-buckle nut in one direction operates to lengthen the cam rod, and rotation of this nut in the opposite direction operates to shorten the cam rod, rotation of this nut in one direction or the other will effect a permanent setting of the adjusting lever 47 to thereby increase or decrease the extent of feeding movement of the feed dog 20 as may be desired.

10 The cam roller 56 is maintained in contact with the surface of the cam 58 by means of a coiled spring 80 the lower end of which is secured to a pin 81, such as the pivot pin between the slide bar 54 and the turn-buckle structure 53, and the upper end of which is secured to the angularly bent end of a supporting rod 82 having its lower end secured to the base portion of the guide member 55.

15 The cam shaft 59 is preferably provided with a brake device 63, as shown in Figs. 1 and 7, for the purpose of controlling the rotation of the cam shaft, and particularly for preventing reverse rotation thereof. This brake device is preferably in the form of two semi-circular clamping members 84 surrounding a collar 85 on shaft 59 and having the lower ends thereof mounted upon a common pivot 86 projecting outwardly from one of the upstanding brackets 60. The clamping members 84 are preferably provided 25 with a suitable lining 87, and the desired friction may be secured by the adjustment of a wing nut 88 on a bolt 89 connecting the free ends of the two clamping members.

20 One end of the cam shaft 59 is also provided with a milled hand wheel 90 for the purpose of manually rotating the shaft and thereby adjusting the elongated stitches *b* into the position desired with respect to the work *w*. The particular location of the elongated stitches with respect to the work having been determined, it is 25 only necessary to rotate the cam shaft 59 by means of the hand wheel 90 so as to bring the operative portion of the cam 58 into a position that one of the inclined surfaces thereof 30 is in engagement with the cam roller 56 in order to definitely locate the elongated stitches on the goods. As illustrated in Fig. 6 of the drawings, the operative portion of the cam 58 has just passed by the cam roller 56 and, as a consequence, the link-bar 40 is in position for making normal stitches *a* of uniform length. Should it be desired to begin the line of stitching with an elongated stitch *b*, the cam shaft 59 may readily be rotated by means of the hand wheel 90 so as 35 to bring the advancing edge of the operative portion of the cam 59 into engagement with the cam roller 56, whereupon the normal operation of the sewing machine will first produce an elongated stitch *b* followed by seven short stitches *a* of uniform length, and this cycle will be repeated 40 throughout the line of stitching.

45 The manner in which two pieces of material such as *c* and *d*, sewed together by the machine disclosed herein, may be utilized with the hook elements *e* of hook and eye fastener devices is illustrated in Figs. 8 and 9 of the drawings. When sewed together with the improved mechanism, a line of stitching is formed in which the elongated stitches *b* occur at regular intervals throughout the normal stitches *a*. The elongated stitches therefore provide gaps through which the operative portions of the hook elements *e* may be inserted in the manner illustrated in Fig. 9.

50 As shown in Fig. 9, the hook elements *e* are

5 attached to a tape *f* formed of a folded strip of suitable material. The strips of material *c* and *d* are folded backwardly over the line of stitching, and the operative portions of the hook elements *e* are inserted through the gaps. The extreme edge of the strip *d* is then preferably turned under the tape *f*, whereupon the tape is secured within the folded strips *c* and *d* by suitable lines of stitching *g*. It will be understood, of course, that the wider strip *c* may be the material of the garment to which the hooks are attached, although in practice it is preferable to attach the tape *f*, with the hooks *e* thereon, to the separate strips *c* and *d* which are thereafter secured to the edge of the garment.

10 It will be understood that Figs. 8 and 9 of the drawings merely illustrate one use which may be made of the form of stitching produced by the machine disclosed herein, and it will be apparent that such stitching is well adapted for other practical uses where stitches of normal length would not provide gaps of the desired length and it would be necessary to increase the length of predetermined stitches at regular intervals throughout the line of stitching.

15 While specific forms and arrangements of the various parts of the improved mechanism have been disclosed, it is to be understood that the disclosure is illustrative only and that changes in form and arrangement of the elements may 20 be made without departing from the invention, the scope of which is to be determined by the appended claims.

25 What I desire to claim as my invention is:

1. In a sewing machine of the type having a 30 bed plate, a standard and bracket arm mounted thereon, a drive shaft mounted in the bracket arm, and a feed link-bar actuated by an eccentric on the drive shaft and fulcrumed upon one end of a link pivoted at its opposite end to one 35 arm of a bell-crank feed adjusting lever pivoted within the standard, the combination of a cam shaft supported on said bed plate parallel to said drive shaft, transmission means between said drive shaft and said cam shaft to rotate 40 said cam shaft intermittently, a cam on said cam shaft, a cam rod actuated in an endwise direction by said cam, and a lever extension rigidly secured at its inner end to said feed adjusting lever and projecting outwardly from said 45 standard with its outer end pivoted to said cam rod to periodically vary the extent of movement of the lower end of said link-bar.

50 2. In a sewing machine of the type having a feed link-bar actuated by the drive shaft and 55 fulcrumed upon one end of a link pivoted at its opposite end to one arm of a bell-crank feed adjusting lever, the combination of a cam shaft, transmission means between said drive shaft and said cam shaft to rotate said cam shaft intermittently, a cam on said cam shaft, a cam rod actuated in an endwise direction by said cam and including a turnbuckle device to adjust the length thereof, and a lever extension rigidly secured at one end to said feed adjusting lever and 60 pivoted at its other end to said cam rod to periodically vary the extent of movement of the lower end of said link-bar.

65 3. In a sewing machine attachment, a cam shaft, a cam fixed on said shaft, a cam rod 70 mounted for endwise movement by said cam and having means for connecting the same to the feed adjusting lever of the sewing machine, a ratchet wheel fixed on said cam shaft, a pawl loosely supported on said cam shaft for actuati- 75

ing said ratchet wheel, a stub shaft parallel to said cam shaft, a crank on said stub shaft, a pitman operatively connecting said crank and said pawl, and means for transmitting continuous rotary motion from the drive shaft of the sewing machine to said stub shaft.

4. In an attachment for automatically varying the length of the stitch of a sewing machine having a bell-crank feed regulating lever, a projecting arm secured to said lever, an intermittently rotated cam, a cam rod actuated in an endwise direction by said cam and including a turn-buckle structure for adjusting the length of said rod, and means for pivotally connecting one end of said cam rod to said projecting arm.

5. In an attachment for automatically varying the length of the stitch of a sewing machine

having a bell-crank lever for adjusting the fulcrum of the feed link-bar, a cam shaft, a cam fixed on said cam shaft, a cam rod actuated in an endwise direction by said cam, and having one end thereof pivotally connected to an arm of said bell-crank lever, a ratchet wheel fixed on said cam shaft for rotating the same step-by-step, a pawl loosely mounted on said cam shaft for actuating said ratchet wheel, a stub shaft parallel to said cam shaft, a crank on said stub shaft, a pitman operatively connecting said crank and said pawl, means for continuously rotating said stub shaft, a brake for resisting reverse rotation of said cam shaft, and manually operated means for rotating said cam shaft. 15

JOHN F. HAND.
